CLAIM

The ornamental design for a 360 degree laser generating
tool, as shown and described.

DESCRIPTION

FIG. 1 is a perspective view of the 360 degree laser
generating tool incorporating my new design;

FIG. 2 is a front view thereof;

FIG. 3 is a top view thereof;

FIG. 4 is a bottom view thereof;

FIG. 5 is a left view thereof;

FIG. 6 is a right view thereof; and,

FIG. 7 is a rear view thereof.

The portions of the 360 degree laser generating tool shown
in FIGS. 4, 5 and 7 in broken lines form no part of the
claimed design.
